UNITED STATES PATENT OFFICE.

HUGO L. STEIDEL, OF ARLINGTON, NEW JERSEY.

STOP ATTACHMENT FOR WINDOW-SHADES.

1,089,731.

Specification of Letters Patent. Patented Mar. 10, 1914.

Application filed January 18, 1913. Serial No. 742,799.

To all whom it may concern:

Be it known that I, HUGO L. STEIDEL, a citizen of the United States, residing at Arlington, in the county of Hudson and State of New Jersey, have invented certain new and useful Improvements in Stop Attachments for Window-Shades; and I do hereby declare the following to be a full, clear, and exact description of the invention, such as will enable others skilled in the art to which it appertains to make and use the same, reference being had to the accompanying drawing, and to figures of reference marked thereon, which form a part of this specification.

This invention is a window shade attachment that is designed to be detachably secured to a window shade, preferably at the bottom or stick end, and to project so as to engage either the window-sash or the window-frame to prevent the snapping of the shade up to and around the roller, if the string by which the shade is operated is released while one of the pawls of the shade roller is not engaged.

It is well known that it very often happens when the shade is released in the above-described manner, it winds around the shade roller a number of times, thus permitting an unwinding of the spring, sometimes damaging the roller or the shade, and also necessitating the rearrangement of the shade from a chair or step-ladder.

To overcome this difficulty I have devised an attachment which engages either the meeting rail of the lower sash on its under face, or the top of the window-frame to halt the shade when it is traveling upward.

The invention is illustrated in the accompanying drawing, in which—

Figure 1 is a section through a window showing the shade and its attachment in elevation. Fig. 2 is an enlarged view showing the bottom end of the shade and its attachment. Fig. 3 is a back view of the attachment removed from the shade.

In the drawing I show an ordinary window-frame 10 with an upper sash 11 and a lower sash 12 and a shade roller 13 on which is mounted the shade 14. The roller is not shown in detail but is of the usual spring roller type which will rapidly wind up if released suddenly in the operation of the shade. The bottom end of the shade has a stick or similar stiffening device 15, and

in this specification and in the claims I call this end of the shade the stick end. Attached to the bottom or stick end of the shade is a plate 16 which is bent down as at 17, and at the bottom end it is bent into a loop 18 and then into an upwardly extending wall 19 whereby a trough is formed into which the stick end of the shade, with its stick 15, is slid. The spring action or the pressing together of the sides of the trough can be utilized to more safely secure the attachment, but I prefer to fasten it by fastening means, such as the screws 20. The plate 16 projects from the shade far enough to permit its engagement with the under side of the top meeting rail 21 of the lower sash 12, as shown at *a* in Fig. 1. It will be understood that if the shade is being manipulated and it suddenly slips from the fingers of the person moving the shade, the shade will move upward until the attachment arrives at the position *a* in Fig. 1 where it will be stopped by its engagement with the meeting rail of the sash. If for some reason it should pass this meeting rail 21, it will stop in the position *b* in Fig. 1, thus preventing the winding of the shade around the roller and the consequent wrapping of the string or cord. If a string or cord is used on a shade supplied with my attachment, the cord will be suspended from the stick end which halts at *b* in Fig. 1, so that it can be grasped, since it is not wound around the shade roller.

To make the descent of the attachment easier and to prevent its being an obstruction when the shade is pulled down, I provide the attachment with the upwardly and outwardly inclined part 22 which can be formed substantially broad as shown in Fig. 3, this portion acting as a fender so that when the shade is pulled down below the meeting rails of the sashes, the inclined face of the portion 22 moves easily over the meeting rail and there is no appreciable stopping of the shade.

The device can be ornamented as desired, and its weight and size will vary somewhat with the character and size of the shade.

The window shade attachment when placed on the outside of the shade and extending a considerable distance above the stick, is thrown away from the roller when the stick end of the roller starts to go over the window shade, and is thus in a sense

projected from the shade so as to positively engage the frame above the roller and halt the shade.

Having thus described my invention,
5 what I claim is:—

1. The combination of a window frame so as to engage the bottom of the rail with window shade, and a stop on the front of the shade and disposed to project therefrom 10 so as to engage the bottom of the rails with its top edge so as to halt the curtain at an intermediate point in its range of travel.

2. The combination of a window frame and sashes having a meeting rail, with a 15 window shade, and a stop at the bottom of the shade and projecting from the front thereof, the stop being arranged so that the rail is in its path of travel whereby the shade can be stopped at a predetermined

point with the stop resting against the bottom edge of the rail.

3. The combination of a window frame and sashes having a meeting rail, with a window shade, and a metal plate formed into a wide trough to receive the stick end 20 of the shade and projecting above the stick and from the front of the shade so as to form a flat top plate to engage the rail, the plate having an upwardly and outwardly inclined curved part extending from the 25 trough to the plate.

In testimony, that I claim the foregoing, I have hereunto set my hand this fourteenth day of January, 1913.

HUGO L. STEIDEL.

Correction in Letters Patent No. 1,089,731.

It is hereby certified that in Letters Patent No. 1,089,731, granted March 10, 1914, upon the application of Hugo L. Steidel, of Arlington, New Jersey, for an improvement in "Stop Attachments for Window-Shades," an error appears in the printed specification requiring correction as follows: Page 2, strike out line 7, and insert the words *and sashes having a meeting rail, with a*; and that the said Letters Patent should be read with this correction therein that the same may conform to the record of the case in the Patent Office.

Signed and sealed this 21st day of April, A. D., 1914.
